DESIGN FOR A DRESS

David Minchenberg, New York, N. Y.

Application May 4, 1944, Serial No. 113,459

Term of patent 14 years

(Cl. D3—26)

To all whom it may concern:

Be it known that I, David Minchenberg, a citizen of the United States of America, residing in New York city, county of New York, and State of New York, have invented a new, original, and ornamental Design for a Dress, of which the following is a specification, reference being had to the accompanying drawing, forming part thereof, wherein,

I claim:

The ornamental design for a dress, substantially as shown.

DAVID MINCHENBERG.
